UNITED STATES PATENT OFFICE.

ELMER C. RIGBY, OF DUNDEE, ILLINOIS.

BUTTER-WORKER.

SPECIFICATION forming part of Letters Patent No. 268,536, dated December 5, 1882.

Application filed June 9, 1882. (No model.)

To all whom it may concern:

Be it known that I, ELMER C. RIGBY, of Dundee, in the county of Kane and State of Illinois, have invented a new and Improved Butter-Worker, of which the following is a full, clear, and exact description.

The object of my invention is to provide a simple and efficient power butter-worker, whereby hand-labor may be superseded.

Reference is to be had to the accompanying drawings, forming part of this specification, in which similar letters of reference indicate corresponding parts in both the figures.

Figure 1 is a plan view of my improved butter-worker with a part of the cover employed for inclosing the gearing above the table broken out. Fig. 2 is a sectional elevation of the improved butter-worker with the aforesaid cover shown in dotted lines.

20 A represents a circular concave table mounted on a vertical pivot, b, set up on any approved bench, d, or other support for an axis around which the table may revolve, the said pivot being stationary.

25 e represents a toothed bevel-wheel attached to the under side of the table, for turning it by a driver, f, to the shaft of which the power is to be applied by a driving-belt and a pulley, g. On the upper side of the table is another toothed wheel, h, for giving motion to the conical rollers i and j by the pinions k, the said rollers being mounted by their outer journals in boxes l, that are capable of shifting up and down in the slotted standards m, and by the journals of the 30 other ends in the bearing-bar n, fitted on the vertical rod b, and being capable of shifting up and down on it, and also being secured anywhere by a set-screw; but its adjustment will be limited to the range of adjustment that the 35 teeth of the wheel h and the pinions will allow.

A cover, o, of sheet metal or other approved material, incloses the pinions k and wheel h to prevent the butter from working onto them, and one or more passages, p, allow the butter-milk to escape through the table into the pan q, arranged on the bench d under the table to receive it, and having central vertical tubular extensions, t, around the rod d. Over the pan is a collar, u, to be fastened on the rod by a set-

50 screw or other means, for the hub of the wheel e and table A to rest and revolve on. Near the outer edge the table also rests on anti-friction rollers v for support and for being carried thereon.

The roller i is made plain on the surface for 55 rolling the butter down smooth, and the roller j is fluted for working it into ridges, so that it will be efficiently worked under each roller.

In practice the wheels e and h may be constructed in one wheel having a double-toothed 60 rim and being constructed with spokes in the common way, the said wheel being let into an opening formed in the table suitable for it.

The table may have a rim rising up from the outer edge, if desired, to prevent the butter 65 from being forced over the edge by the rollers; but if made sufficiently concave the rim may not be required.

With a machine of the above-described character the laborious methods of working butter 70 by hand may be avoided, the said machine being competent to do all the work with a little attention quite as well as by hand and much more rapidly.

Having thus fully described my invention, 75 what I claim as new, and desire to secure by Letters Patent, is—

1. The combination, with a table dished toward the center and loose upon a fixed vertical shaft, of a smooth conical roll, i, and a 80 fluted conical roll, j, both revolved on their axes while the table is revolved under them, as described.

2. In a butter-worker, the crown-wheels h e, clamped respectively to the top and bottom of 85 the table A, to connect the cone-pinions k with the drive-wheel f, as described.

3. The combination, with the fixed vertical rod b and the cone-driving pinions k k, of the horizontal bar n, arranged at its middle loosely 90 on said rod b, and provided at each end with a bearing for the journals of said pinions k, as shown and described.

ELMER C. RIGBY.
